Frank G. Back, New York, N. Y.

Application March 5, 1952, Serial No. 18,786

Term of patent 7 years

(Cl. D57—7)

To all whom it may concern:

Be it known that I, Frank G. Back, a citizen of the United States, residing in the city, county, and State of New York, have invented a new, original, and ornamental Design for a Testing Device for Optical Lenses and the like, of which the following is a specification, reference being had to the accompanying drawing, forming part thereof.

Fig. 1 is a top plan view of a testing device for optical lenses and the like, embodying my new design;

Fig. 2 is a side elevational view of the testing device for optical lenses and the like; and

Fig. 3 is an end view thereof.

I claim:
The ornamental design for a testing device for optical lenses and the like, as shown.

FRANK G. BACK.
